(57) **CLAIM**

The ornamental design for an interrupter for irrigation controller, as shown and described.

DESCRIPTION

FIG. 1 is a top perspective view of an interrupter for an irrigation controller of the present invention with a front panel closed.

FIG. 2 is a rear plan view of the interrupter for an irrigation controller of FIG. 1.

FIG. 3 is a front plan view of the interrupter for an irrigation controller of FIG. 1.

FIG. 4 is a side view of the interrupter for an irrigation controller of FIG. 1.

FIG. 5 is a top plan view of the interrupter for an irrigation controller of FIG. 1.

FIG. 6 is a top perspective view of an interrupter for an irrigation controller of the present invention with a front panel open; and,

FIG. 7 is a front plan view of the interrupter for an irrigation controller of FIG. 6.

The broken line showing of unclaimed portions of the interrupter for irrigation controller forms no part of the claimed design.
